SHUTTERING BOARD

William Galloway Duncan, London, England, assignor to Interlox Structures Limited, London, England

Application May 7, 1940, Serial No. 333,865
In Great Britain July 13, 1939

2 Claims. (Cl. 72—16)

This invention relates to improvements in the construction of walls, partitions, slabs, roofs or floors or the like by employing shuttering between or on which a material, such as concrete, is poured and then left to set.

The primary object of this invention is to provide a construction in which the interior surface of the finished wall or the like is insulated from the exterior, thus ensuring waterproofing, and, further, forming an insulation against changes in temperature. A further object is to provide an interior surface which can be readily treated to suit desired internal decorations. With these and other objects which will be apparent from the following specification, the invention may be said to consist in a lining or permanent shuttering for a wall, ceiling or floor surface, for use wherein the wall or the like is constructed from concrete or like material which is cast in situ between or on shuttering, comprising a front sheet or board having a face of desired characterization, and a rear board of sound and heat insulating material, the two said boards comprising a unitary lining or permanent shuttering for one or both faces of the wall or the like, the rear board being formed or provided with means which will key with the pourable material.

With such a construction, the face of the front board can be arranged to present any desired surface which lends itself to suitable finishing. For example, the front board may be of hard wood and the face thereof polished, painted or otherwise treated. Other suitable materials, such as plaster, ply or cement board or linoleum, may, however, be used.

Further, the rear board has the required physical properties and is therefore constructed from a heat and sound insulating material, such as a board including cork or fibre in its composition. It will be understood that the rear board is arranged to key directly with the concrete and in practice a suitable waterproof lining or coating may be given to the rear of the said board. Further, the two boards may be united by a waterproof cement or like material.

In order that a clear understanding of the invention may be obtained, reference will now be made to the accompanying sheet of drawings which illustrate shuttering constructed in accordance with the invention, and a preferred method of building a wall and ceiling therewith. In the drawings:

Figure 1 is a perspective view of a portion of shuttering constructed in accordance with the invention.

Figure 2 is a sectional view showing an alternative method of keying; and,

Figure 3 is a perspective view illustrating diagrammatically a preferred method of construction employing the shuttering.

Referring first to Figures 1 and 2, the shuttering comprises a foundation or rear board 1 conveniently of wood, plywood or composition fibrous board. Any material which possesses rigidity and sufficient strength and has good sound and heat insulating properties may be employed. A sheet of hard wood, composition board, cork or other material 2 is secured to one face of said foundation by suitable means such as by waterproof cement 3, the exposed face of said sheet forming the surface of the finished wall or slab, and therefore being selected to present the required surface.

The other face is arranged so that the concrete will bind thereto, and suitable keyways or the like are provided. For example, in Figure 1 a number of undercut or dovetail strips 4 are secured to the said face, said strips being of hard fibre board, wood, sheet steel or other suitable material. In Figure 2, undercut apertures, one of which, 5, is shown, are formed in the foundation or rear board 1 at suitable spaced-apart points, that is, as shown, the apertures 5 are wedge-shaped with the wedge end of smaller width thereof on the exposed face of rear board 1. After the keyways or the like have been formed in or on or secured to the board the rear surface thereof is treated or coated with a waterproof material or layer 6.

In use, the material, such as concrete, is poured in the usual way, and, for walls, the shuttering is built up and suitably supported, one side at least consisting of the improved shuttering above set out.

In cases where the external wall or like surface is to form an outside surface, a shuttering consisting of board may be employed. Referring to Figure 3, said boards 7 are conveniently plywood boards, the layers of which are secured together by means of a waterproof cement, preferably a synthetic resinous material. Such boards are extremely rigid and durable and, moreover, are not materially affected by heat or water. Further, the said boards may be employed in the construction of the internal shuttering hereinbefore described.

It will be understood that both faces may be formed by the improved shuttering herein described and suitable means will be provided for

spacing the two layers in correct spaced-apart and parallel relation.

In Figure 3, the support for the rear shuttering comprises lattice work 8 which is constructed from angle iron, said lattice work being held in position and braced by suitable means, not shown, and, if necessary, secured to the shuttering until after the initial setting of the concrete 9.

The inner shuttering comprises a number of boards held in co-planar position as shown, while the ceiling is similarly constructed, the boards being suitably supported until after setting of the concrete roof 10.

By employing the shuttering herein described, the internal surface can be directly painted or otherwise treated, no plastering or other similar treatment being necessary. Further, an unbroken surface is presented and no holes are left as split bolts are not employed. Electric or other conduits, window and door frames can be supported in position prior to the pouring of the concrete or like material. The improved shuttering may also be employed for party walls, in which case it is merely supported in position.

I claim:

1. A composite board for use in constructing

permanent shuttering, comprising a front layer formed of ornamental hard wood, a rear layer of sound and heat insulating material, said front and rear layers being cemented together by a 5 layer of waterproof adhesive cement, said rear layer being provided with spaced keyways of wedge section having the wedge end of smaller width on the exposed face of said rear layer, said keyways being adapted to receive molded 10 projections formed in situ on moldable material applied to said exposed face.

2. A composite board for use in building up permanent shuttering comprising a front layer having an ornamental face, a rear layer of heat 15 and sound insulating material, an interstitial adhesive waterproof layer uniting said rear insulating layer to said front ornamental layer, said rear insulating layer being provided with a plurality of spaced apart undercut apertures formed 20 therein adapted to receive keying projections formed in situ as moldable material applied to said rear insulating layer, and a thin outer waterproof layer covering the rear outer surface of said rear insulating layer and the portions exposed by said undercut apertures.

25 WILLIAM GALLOWAY DUNCAN.
